CLAIM

The ornamental design for a decorated data storage disk, as shown and described.

DESCRIPTION

FIG. 1 is a front perspective view of a decorated data storage disk showing my new design;

FIG. 2 is a right side view thereof;

FIG. 3 is a left side view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines shown in the drawings depict environmental structure that forms no part of the claimed invention.
